UNITED STATES PATENT OFFICE.

CARL ROCHELLE, OF WASHINGTON, NORTH CAROLINA.

FEED-WATER HEATER.

1,180,078.

Specification of Letters Patent. Patented Apr. 18, 1916.

Application filed June 19, 1914. Serial No. 846,098.

To all whom it may concern:

Be it known that I, CARL ROCHELLE, a citizen of the United States, and a resident of Washington, in the county of Beaufort 5 and State of North Carolina, have made certain new and useful Improvements in Feed-Water Heaters, of which the following is a specification.

My invention relates to improvements in 10 feed water heaters, especially those used in connection with locomotive boilers, and it consists in the combinations, constructions, and arrangements herein described and claimed.

15 An object of my invention is to provide a device by means of which the water with which the boiler is charged may be heated prior to its admission to the boiler by heat from the fire box, with means for preventing 20 a disastrous discharge of steam into the cab of the engine from the fire box in the event of the burning out of the water heating parts which are disposed in the fire box.

A further object of my invention is to 25 provide a novel form of safety device for boilers which are provided with feed water heaters, which may be readily attached and which will prevent dangerous explosions, while at the same time serving as a means 30 for keeping the water heater filled with water at all times, thereby lessening the danger of the burning out of the water heater.

Other objects and advantages will appear 35 in the following specifications and the novel features of the device will be particularly pointed out in the appended claims.

40 My invention is illustrated in the accompanying drawings forming part of this application in which—

Figure 1 is a side view of a boiler, one of the water heaters being shown in section, Fig. 2 is a section along the line 2—2 of Fig. 1, looking in the direction of the arrows, Fig. 3 is an enlarged detail view of a check valve, and Fig. 4 is a sectional view through a by-pass and a check valve of the intake pipe.

45 In carrying out my invention I make use 50 of any suitable form of boiler, but the invention is particularly adapted for boilers

of the water-tube type, such as those used on locomotives.

Referring now to the drawings 1 denotes the ash pit, 2 the grate bars and 3 the interior of the fire box. Disposed on the sides of the fire box are water heating compartments 4 and 5 respectively. Each of these compartments is provided with a series of baffles 6, adjacent baffles extending from 60 opposite ends and terminating so as to leave a passage 6^a at opposite ends of adjacent baffles. The water heating compartments 4 and 5 besides being the means of heating the feed water also serve as means for preventing 65 the burning out of the side of the fire box thereby dispensing with the need of refractory linings at these places.

From Fig. 1, it will be seen that a steam pipe 7 extends from the top of the boiler 70 which I have denoted in general by B to an injector 8, which may be of any suitable type, and which is connected with a cold water inlet pipe 9 in the usual manner. The end of the injector is connected with a pipe 75 10 which enters the boiler at 11. A cut-out cock 12 is provided in the pipe 10.

Communicating with the pipe 10 between the cut-out cock and the injector 8 is a pipe 13 which is provided with a check valve 14. 80 The pipe 13 enters the compartment such as that shown at 5 at or near the bottom, while a pipe 15 communicates with the top part of the compartment and enters the boiler at 16. The pipe 15 is provided with a check 85 valve 17. A by-pass 18 is placed around the check valve 17 and is provided with a shut-off cock 19.

The description of the feed water connections has been in connection with the apparatus on one side of the boiler, but it will be understood that a duplicate arrangement is provided for the other side of the boiler. Thus the members 7 to 19 inclusive have corresponding members 7' to 19' inclusive 95 on the opposite side of the boiler. In Fig. 4 it will be seen that the by-pass 18 is relatively small as compared with the pipe 15. The arrangement of these pipes forms one of the main features of the invention as will 100 be fully pointed out hereinafter.

From the foregoing description of the

various parts of the device the operation thereof may be readily understood. Cold water enters the injector through the pipe 9, while steam enters through the pipe 7. 5 When the stop-cock 12 is closed water is injected through the pipe 13 into the lower part of the compartment 5 on one side, from whence it flows around the baffles or partitions 6 thence flowing through the pipe 15 10 and past the check valve into the boiler. The water is preheated by its passage through the compartment 5 which forms the side of the fire-box so that when it enters the boiler little heat is required to generate steam. 15 The water compartment in the fire box forms a protection to the wall of the fire box, thereby preventing the burning out of the latter.

When the fire box is cooled off, the presence of the by-pass 18 will keep the water heating compartments filled because the water in the boiler will flow through the by-pass into the water heating compartments, so that when the fire box is again heated up 25 these compartments will be filled with water and will not be burned out under the ordinary circumstances.

If after long continued use or through accident or injury to the interior wall of the 30 compartments a break should occur, steam from the boiler cannot pass back into the water heating compartment with sufficient force to injure those in the cab, because of the fact that the by-pass is too small to prevent it.

The device is designed to prevent accidents in which feed water heaters have parts exposed to the direct action of the fire in the fire box which are liable to be burned out 40 and thereby permit the steam to flow back through the fire box into the cab, thus injuring the occupants of the cab. It will be noted that the by-pass 18 serves the double purpose of permitting water to flow back 45 so as to fill the water heating compartments when the latter have cooled off. It will be understood that this return flow is very slow owing to the small diameter of the by-pass, but nevertheless it is entirely sufficient for 50 the purpose because it takes time after the water heater has cooled off to fire up and this time is amply sufficient to permit the filling of the water heater. Of course, if the water heater should burn out the check 55 valve 17 which opens to permit the water to enter the boiler would prevent the return of steam and water into the water heater. The by-pass 18 is so small that the little amount of steam which is forced back 60 around the by-pass will not cause an explosion in the fire box and will give plenty of time to the engineer or fireman to close the stop cock 19 in the by-pass, thereby pre-

venting any other return flow of water or steam.

Another feature to which I desire to call attention is the fact that if through any accident the water heater should be put out of commission the stop cock 12 may be turned so as to permit the entrance of water 70 through the pipe 10.

I am aware that feed water heaters having a compartment in the fire chamber have been used before but I know of no arrangement by which the water is permitted to enter the boiler after being heated with means for preventing a disastrous flow of steam back into the heater and at the same time permitting a slow flow of water into the heater.

I claim:

1. The combination with a boiler and an injector, of a feed water heater disposed between the injector and the boiler, connections between said injector, said feed water heater, and said boiler, and means for maintaining a full supply of water in said water heater when the latter has cooled off.

2. The combination with a boiler and an injector, of a feed water heater disposed between the injector and the boiler, connections between said injector, said feed water heater, and said boiler, and means for maintaining a full supply of water in said water heater when the latter has cooled off, said last named means also preventing an undue flow of steam from the boiler into the water heater.

3. The combination with a boiler and an injector, of a feed water heater disposed between the injector and the boiler, connections between said injector, said feed water heater, and said boiler, means in said connection for permitting a full flow of water from the water heater into the boiler, and for permitting a slow return of the water 105 from the boiler into the feed water heater when the latter has cooled off.

4. The combination with a boiler and an injector, of a feed water heater disposed between the injector and the boiler, connections between said injector, said feed water heater, and said boiler, means in said connection for permitting a full flow of water from the water heater into the boiler, and for permitting a slow return of the water 115 from the boiler into the feed water heater when the latter has cooled off, said last named means serving to prevent an undue flow of steam from the boiler into the water heater when the latter has burned out.

5. The combination with a boiler and an injector, of a feed water heater disposed between the injector and the boiler, connections between said injector, said feed water heater, and said boiler, a check valve disposed in the connections between the boiler

and the water heater for permitting a full flow of water from the water heater into the boiler, and a by-pass of relatively small cross sectional area around said check valve for permitting a slow return of water from the boiler into the water heater when the latter has cooled off, while preventing an undue

flow of steam from the boiler into the water heater when the latter has burned out.

CARL ROCHELLE.
